(57) **CLAIM**

The ornamental design for an anti-vortex safety cover for a drain, as shown and described.

DESCRIPTION

FIG. 1 is a stop plan view of an anti-vortex safety cover for a drain embodying my new design; FIG. 2 is a side elevation view thereof; FIG. 3 is a bottom plan view thereof; and, FIG. 4 is a cross section thereof as taken along line 4—4 of FIG. 3.

The broken line showing is for illustrative purposes only and forms no part of the claimed design.
